US0D1045297S

(12) **United States Design Patent** (10) **Patent No.:** **US D1,045,297 S**
(45) **Date of Patent:** **** Oct. 1, 2024**

(54) **MOBILE CLEANING ROBOT**

(71) Applicant: **iRobot Corporation**, Bedford, MA (US)
(72) Inventors: **Calvin Jinwon Lee**, Nashua, NH (US); **Shipra Arora**, Cambridge, MA (US); **Rick Hoobler**, Waltham, MA (US); **Insun Hong**, Somerville, MA (US); **Benjamin H. Schriesheim**, Watertown, MA (US)

(73) Assignee: **iRobot Corporation**, Bedford, MA (US)

(**) Term: **15 Years**

(21) Appl. No.: **29/746,568**

(22) Filed: **Aug. 14, 2020**

(51) LOC (14) Cl. **15-05**

(52) U.S. Cl.

USPC **D32/21**

(57) **CLAIM**

The ornamental design for the mobile cleaning robot, as shown and described.

DESCRIPTION

FIG. 1 is a top-right-isometric view of a first embodiment of our mobile cleaning robot, showing the new design;

FIG. 2 is a rear view thereof;

FIG. 3 is a front view thereof;

FIG. 4 is a right-side view thereof;

FIG. 5 is a left-side view thereof;

FIG. 6 is a top view thereof; and

FIG. 7 is a bottom view thereof.

FIG. 8 is a top-right-isometric view of a second embodiment of our mobile cleaning robot, showing the new design;

FIG. 9 is a rear view thereof;

FIG. 10 is a front view thereof;

FIG. 11 is a right-side view thereof;

FIG. 12 is a left-side view thereof;

FIG. 13 is a top view thereof; and,

FIG. 14 is a bottom view thereof.

The broken lines shown in the figures are for the purpose of illustrating portions of the mobile cleaning robot that form no part of the claimed design.

1 Claim, 10 Drawing Sheets
